US00D956123S

(12) **United States Design Patent** (10) **Patent No.:** **US D956,123 S**
(45) **Date of Patent:** **** Jun. 28, 2022**

(54) **CAMERA**

(71) Applicant: **GoPro, Inc.**, San Mateo, CA (US)

(72) Inventors: **John George Muhlenkamp, IV**,
Brisbane, CA (US); **Huy Phuong
Nguyen**, Alpine, UT (US); **Daniel J.
Coster**, Oakura (NZ)

(73) Assignee: **GoPro, Inc.**, San Mateo, CA (US)

(**) Term: **15 Years**

(21) Appl. No.: **29/814,777**

(22) Filed: **Nov. 9, 2021**

Related U.S. Application Data

(62) Division of application No. 29/785,302, filed on May 25, 2021, which is a division of application No. 29/706,013, filed on Sep. 17, 2019, now Pat. No. Des. 920,419.

CLAIM

The ornamental design for a camera, as shown and described.

DESCRIPTION

FIG. 1 is a top, front and left perspective view of a camera showing our new design;

FIG. 2 is a bottom, rear and right perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken lines depict portions of the camera that form no part of the claimed design.

1 Claim, 8 Drawing Sheets
